Filed July 22, 1957, Ser. No. 673,474
8 Claims. (Cl. 34—62)

This invention relates to apparatus for drying and conditioning textile fabrics. While the invention may be described more particularly in connection with the treatment of tubular knit materials, it may be utilized in handling woven materials and other forms of knit goods, as may be desired.

In connection with the treatment of many textile materials, it is frequently necessary to dry the material, as by passing the material in contact with dry, heated air. After drying, the material may be further processed, and eventually wound into rolls or folded. One form of apparatus for drying a web of material is shown in United States Patent No. 2,637,991, to S. Cohn, et al., issued May 12, 1953. This apparatus comprises a large housing in which are supported a plurality (usually 6) of large diameter dryer reels arranged in staggered relation. A web of moist material enters the housing at one end and passes sinuously about the dryer reels, in series. As the material passes about the reels, streams of heated air are directed toward the exposed surface of the material, so that the moisture is driven from the material and carried away by the heated air. The present invention relates to a dryer apparatus of this type which is characterized by certain specific structural and mechanical improvements which render the apparatus more versatile and more efficient in its operation.

One of the specific aspects of the invention resides in the provision of a reel dryer unit of modular design, which is adapted for use individually or in combination with one or more similar units to effect the continuous drying of an elongated web of material. In this respect, the requirements of various material processing businesses vary widely in respect of the desired capacity of drying apparatus. Thus, some materials are more easily dried than others, and some material conditioning operations impart more moisture to the material than others. Accordingly, the present invention seeks to provide a dryer unit which, by itself, has a desired capacity suitable for a business having minimum capacity requirements, while at the same time being adapted for use in tandem or multiple arrangement to suit the capacity requirements of all processors.

More specifically, the invention provides an improved modular drying unit having a pair of dryer reels disposed one above the other in a more or less rectangular housing. The operative elements of the dryer unit are such that the material enters the dryer housing horizontally, passes first about one and then the other of the dryer reels, and then passes horizontally out of the housing at substantially the same level as it entered. If the nature of the material and/or the preceding treatment is such that additional drying capacity is required, two or more of the modular drying units may be placed end to end, in series, so that the material may be passed through as many units as is required.

As the material passes through the dryer units, it becomes heated to a substantial degree and leaves the last dryer reel at a relatively high temperature. Accordingly, it is desirable that the material be cooled prior to leaving the dryer housing, and it is one of the specific features of the invention to provide an improved arrangement for directing streams of cooling air upon the opposite surfaces of a web of material as it leaves the dryer hous-

2

ing. Further, in this respect, the modular dryer unit of the invention includes means effective when two or more dryer units are arranged in series to convert the cooling means of all dryer units except the last to means for further heating and drying the material. To this end, the dryer units include novel structural arrangements which permit the units to be readily adapted to the requirements of the user.

Another specific feature of the invention resides in the provision of improved arrangements for circulating drying air through and about the web of material as it passes over the dryer reels. To this end, the opposite ends of the dryer reels are fully opened to a low pressure chamber leading to the intake or intakes of one or more blower devices. The arrangement is such that air passing through the fabric and into the center portion of the dryer reels flows uniformly from each end of the reels, to effect uniform drying of the fabric across its entire width.

During the process of drying the material, the drying air becomes laden with moisture and must be discharged and replaced with fresh, relatively moisture-free air. In this respect, one of the improved features of the invention resides in an arrangement for drawing cool, relatively moisture-free air into the dryer housing and discharging such air over and about the bearings of the blowers. By this means, the bearings of the blower are maintained at a lower temperature and therefore have a longer operating life.

As a general rule, moist material passing through a dryer will tend to shrink to some extent as the moisture is removed progressively therefrom, and the material entering the dryer will be traveling at a greater rate of speed than when it leaves the dryer. For this reason, it is conventional to utilize the material itself to control the speed of the dryer reels and other related apparatus. This may be accomplished by providing suitable dancer rolls which contact the web of material and operate to slow down or speed up the individual reels and other apparatus in accordance with the tension of the material. A known arrangement for this purpose is disclosed and claimed in United States Patent No. 2,301,249, issued November 10, 1942, to H. W. Butterworth, Jr., et al. In accordance with one aspect of the invention, an improved arrangement is provided for controlling the operating speeds of the various drying rolls and other apparatus whereby the speed control is rendered highly sensitive and quickly responsive to the condition of the material, so that undesirable looseness or tension in the material is minimized.

A further feature of the invention resides in the provision of an improved folder apparatus which may be advantageously utilized to receive the cloth after drying and form it into neat, flat folds. The improved folding apparatus may be constructed generally in accordance with United States Patent No. 2,761,678, but incorporates certain novel features which simplify the construction and operation of the apparatus.

Other features of the invention relate to specific structural features of the modular dryer unit which simplify the manufacture thereof and render the apparatus more suitable for its intended purpose.

For a better understanding of the invention, reference should be made to the following detailed specification and accompanying drawings in which:

65 FIG. 1 is a side elevation of the improved modulator dryer unit with parts broken away to illustrate certain features of construction;

FIG. 2 is a cross-sectional view taken generally along line 2—2 of FIG. 1;

70 FIG. 3 is a fragmentary front elevation of the dryer unit of FIG. 1, showing adjustable air intake doors incorporated therein;

FIG. 4 is an enlarged fragmentary view of the apparatus of FIG. 1, illustrating details of the control means utilized therein for regulating the speed of the drying rolls and other apparatus;

FIGS. 5 and 6 are enlarged views of alternate forms of control elements which may be utilized in the control arrangement of FIG. 4;

FIG. 7 is an enlarged fragmentary view of the apparatus of FIG. 1, illustrating details of the means for discharging heated air upon the material;

FIG. 8 is a fragmentary elevation of an improved folding device which may be advantageously used with the apparatus of FIG. 1;

FIG. 9 is an enlarged fragmentary cross-sectional view taken generally along line 9—9 of FIG. 8;

FIG. 10 is an enlarged fragmentary top plan view of the mechanism of FIG. 9;

FIG. 11 is a simplified, schematic representation of an improved drive control arrangement for the system of the invention; and

FIG. 12 is a simplified, schematic representation illustrating a pair of drying units arranged in tandem in accordance with one significant aspect of the invention.

Referring now to the drawings and initially to FIGS. 1-3 thereof, the reference numeral 10 designates generally a housing of more or less cubic form, having side walls 11, 12, front and back end walls 13, 14, and a top wall 15. Within the housing 10 is a drying chamber, outlined by a frame structure 16, including pairs of horizontal supports 17, 18 located respectively above and below the center of the housing. Mounted on the upper support 17, in suitable bearings 19, is a dryer reel 20, which may be of conventional construction, having a peripheral wall formed of wire or other perforate material. Directly below the reel 20 is a second reel 21, journaled in bearings 22 mounted on the lower supports 18. In the illustrated form of the invention, the reel 21 is mounted directly below the reel 20.

Surrounding the upper portion of the upper reel 20 is a duct 23 of generally inverted U-shaped form, which extends from side to side of the reel as shown in FIG. 2, and extends circumferentially about the reel for about 240 degrees, leaving only the lower portion of the reel exposed. The duct 23 has an inner wall 24 in the form of a segment of a circle which conforms closely to the outer surface of the reel 20, being spaced therefrom a small distance, as shown in FIG. 1. At closely spaced intervals about the inner wall 24 of the duct are discharge openings 25, to be described in more detail, which are disposed transversely of the reel 20 in such manner as to permit streams of air to be discharged toward the reel from one side to the other thereof. A duct 26 is also positioned about the lower reel 21, the lower duct 26 being of substantially the same construction as the upper duct 23 but installed in inverted relation whereby the upper portion of the lower reel is exposed.

At the right hand end of the housing 10, as viewed in FIG. 1, are blowers 27, 28, which are advantageously of a type comprising squirrel cage rotor members 29, having intake openings at their opposite axial ends. The outlets 30, 31 of the respective blowers 27, 28 discharge into the ducts 23, 26, to supply air under pressure to these ducts.

As shown in FIG. 2, the side walls 11, 12 of the housing 10 are spaced outwardly of the open ends of the dryer reels 20, 21 and define relatively large end chambers 32, 33 in the opposite sides of the housing. The end chambers 32, 33 are in open communication with the interiors of the dryer reels 20, 21, and are also in communication with the intake openings at the opposite ends of the blower rotors 29. Advantageously, heaters 34, 35 are mounted in the housing 10 between the respective chambers 32, 33 and the blowers 27, 28, so that the air is heated to a desired temperature before flowing through the blower and being discharged into the ducts 23, 26.

As is shown clearly in FIGS. 1 and 2, the area of the end chambers, measured in a vertical plane, is of substantial size, including the end areas of the reels themselves together with the areas of the end walls of the hot air ducts 23. The width of the end chambers is quite substantial and, in any event, sufficiently large to accommodate the heaters 34, 35 disposed between the end walls of the hot air ducts and the side walls 11, 12 of the housing. In one particularly advantageous embodiment of the invention, specifically illustrated herein, the width of the end chambers is in excess of 50% of the diameter of the reels.

Approximately centrally located in the front wall 13 of the housing is horizontally elongated opening 36 through which a web of material 37 is passed. A guide or intake roller 38 is mounted adjacent the opening 36 and serves to guide the web of material 37 through the opening in the desired manner. In the illustrated form of the invention, it is contemplated that the roll 38 will be driven, by a suitable means to be described, the speed of the roller 38 being determined automatically by the condition of the material as it leaves preceding equipment. The material entering the housing 10 is passed about a dancer roll 39, supported by a pivoted arm 40, and is then passed about a substantial portion (approximately 240 degrees) of the periphery of the upper dryer reel 20. As the material leaves the upper reel 20 it is passed about a second dancer roll 41 supported by a counter-weighted, pivoted arm 42, and is then passed about a substantial portion (approximately 300 degrees) of the periphery of the lower dryer reel 21. The material leaving the reel 21 is passed about a fixed guide roller 43 and then about a dancer roll 44 supported by a pivoted, counter-weighted arm 45.

Where the new modulator dryer unit is utilized individually, as distinguished from in tandem or multiple arrangement, the material passing over the third dancer roll 44 is passed between a pair of sealing rollers 46, 47, to be further described, and passes out of the housing 10 through an elongated passage 48. The material leaving the housing 10 may go directly to a folding apparatus such as illustrated in FIG. 8, to be described in greater detail.

When the dryer apparatus is in operation, the blowers 27, 28 are directing heated air under pressure into the hot air ducts 23, 26 surrounding dryer reels 20, 21, and streams of the heated air are discharged from the transverse openings 25 toward the surfaces of the reels. As the material 37 passes consecutively about the upper and lower reels 20, 21, first one side and then the other of the material is exposed to the streams of heated air, so that moisture is picked up by the air and thereby removed from the material. The material, of course, is of a porous nature, as are the surfaces of the dryer reels 20, 21, so that the streams of heated air directed radially toward the dryer reels pass through the material and through the outer walls of the reels. The moisture-laden air in the interior of the reels is drawn axially out of the reels, from the opposite ends thereof into the low pressure chambers 32, 33. The air is then drawn from the chambers 32, 33, through the heaters 34, 35, into the intakes of the respective blowers 27, 28 for recirculation.

As the drying operation progresses, the air circulating within the housing becomes laden with moisture and must be discharged and replaced with fresh air. To this end, an exhaust duct 49 is provided on the front wall 13 of the housing with openings 50 communicating with the respective chambers 32, 33, at opposite sides of the hot air duct 23. The exhaust duct 49 also has a portion 51 which extends downwardly along the front wall 13 of the housing, terminating at or slightly above the material inlet opening 36. An exhaust fan 52 is housed in an exhaust stack 53 for drawing moisture-laden air out of the chambers 32, 33, as well as for drawing in any moisture-laden air which may tend to escape through the material inlet opening 36. Advantageously, the exhaust

stack 53 is provided with an adjustable damper 54 to provide for regulation of the exhausted air.

As moisture-laden air is exhausted from the housing 10, such air must be replaced with fresh air from the atmosphere. Advantageously, at least a portion of such fresh air may be drawn in through small intake ducts 55, 56 (see FIG. 2) which have inlet openings exposed outside of the housing 10 and discharge outlets adjacent the bearings (such as indicated at 57) of the blower rotors 29. The arrangement is such that fresh, cool air flows in through the duct 55, 56 and is discharged over and about the bearings 57 to aid in maintaining such bearings at a relatively low operating temperature.

In the illustrated apparatus, additional means are provided for admitting fresh air into the housing 10, to provide for an increased supply of fresh air where desired. Thus, as shown in FIG. 1 and FIG. 3, directly below the material inlet opening 36 is a fresh air opening 58 which may be controlled by a pair of sliding doors 59, 60. The opening 58 communicates with the end chambers 32, 33 leading to the intake openings of the blowers 27, 28. The doors 59, 60 may be advantageously positioned at any point between fully opened and fully closed positions to facilitate regulation of the supply of fresh air.

As the material travels around the dryer reels 20, 21 it becomes heated to a relatively high temperature, and it is therefore advantageous to cool the material somewhat before it is further processed, as by the folder in FIG. 8. To this end, the new dryer unit is provided with cooling air ducts 61, 62 which are respectively above and below the chamber 48 and, in effect, define the chamber 48. As shown in FIG. 1, the cooling air ducts 61, 62 are horizontally disposed and extend for a substantial length in the direction of movement of the material. At their outer ends, the ducts 61, 62 are connected to the outlet of a blower 63 arranged to draw air from the atmosphere. Cool air supplied to the ducts 61, 62 is discharged therefrom through transverse slots or openings 64 extending transversely of the material, whereby streams of cool air are directed upon the opposite surfaces of the material.

In accordance with the invention, the cooling chamber 48 is isolated from the heating or drying chamber by means of the sealing rollers 46, 47 between which the material passes before entering the chamber 48. As shown in FIG. 1, sealing rolls 46, 47 are in contact with the material and, at their opposite sides, are in close proximity to walls 65, 66 of the hot air ducts 23, 26. The arrangement is such that the rollers 46, 47 effectively isolate the heating and cooling chambers, while permitting the material to move freely from one chamber to the other.

Cooling air discharged into the chamber 48 is, in part, exhausted therefrom through opening 67 at the opposite sides of the chamber, near the outer or right hand end thereof. In addition, some of the air flows along with the material and is discharged at the end of the chamber 48.

One of the important features of the invention resides in the modular design of the dryer unit, whereby two or more units may be arranged in series relation to provide increased drying capacity. In such cases, it is generally not desirable to provide for cooling of the material as it leaves one dryer unit and travels to a subsequent unit. Accordingly, when two or more dryer units are used in series, the blower 63 is removed, as by removing bolts 68 which secure the blower housing to the dryer unit. In addition, removable walls 69, 70 at the inner ends of the cooling ducts 61, 62 are taken out, so that the ducts 61, 62 are in direct communication with the hot air ducts 23, 26. With this arrangement, hot air is supplied to the ducts 61, 62 and is directed upon the material as it travels through the chamber 48. The invention contemplates that, as the material emerges from the outer end of the chamber 48, it will pass directly into a sub-

sequent unit for further drying. The number of units employed may be as high as necessary to provide the desired drying capacity, and it will be understood that the last one of the units will generally be arranged to cool the material as it passes through the chamber 48.

One of the improved structural features of the invention resides in the construction of the hot air ducts 23, 26, as shown in greater detail in FIG. 7. In accordance with known design principles, it is desirable to provide the hot air ducts with a large plurality of closely spaced openings disposed transversely of the material and extending across its width, whereby as the material travels about the dryer reels 20, 21 streams of hot air are directed upon the material to promote efficient drying of the material. The invention provides an improved and simplified structural arrangement for providing the desired slots in the hot air ducts with a minimum of manufacturing cost, and in a manner such that the construction of the duct work is generally simplified. Thus, in accordance with the invention, the hot air ducts may be formed of a pair of generally U-shaped side panels 71, 72 which are positioned at the opposite ends of the dryer reels 20, 21. Extending between the side panels 71, 72, at closely spaced intervals are channel shaped members 73 having tab portions 74 at the ends thereof which are bent at right angles to the members 73 and overlap the side panels 71, 72. The arrangement is such that the channel shaped members 73 may be rigidly secured to the panels 71, 72, by bolting or otherwise securing the tab 74 to the respective panels. As shown in FIG. 7, the channel shaped members 73 are disposed in parallel relation and are spaced a short distance apart whereby to define between them elongated slots or openings 75 extending from one side to the other of the ducts. The side walls or flanges of the channel shaped members 73 are divergently related, so that openings 75 between adjacent channel shaped members 73 are more or less in the form of convergent nozzles. The arrangement is such that air is discharged from the openings 75 in relatively concentrated streams, and considerable turbulence is set up between adjacent openings to promote efficient drying of the material.

In order to reduce the flow of air axially from the ends of the nozzle-like openings 75, small baffle plates 76, of generally trapezoidal form, are secured to the panels 71, 72 to restrict ends of the openings 75. A slight flow of air axially from the spaces between the hot air ducts and the dryer reels is not particularly objectionable.

In a normal drying operation, it can be expected that the material will shrink somewhat as the moisture is removed therefrom and various tensions in the threads of the material are relieved. To accommodate such shrinkage and to prevent the material from being unduly stressed, it is conventional to utilize the various dancer rolls 39, 41, 44 to control the speed of the reel 20, reel 21 and the related processing or handling apparatus, such as the folder of FIG. 8. In addition, the speed of the intake roller 38 is usually controlled by a dancer roll (not shown) which is carried by the equipment preceding the dryer. Controlling the operation of the various components of the apparatus in this manner is, of course, well known in the general sense, and is described in United States Patent 2,301,249, issued November 10, 1942, to H. W. Butterworth, Jr., et al. However, in accordance with one aspect of the invention, improved control arrangements are provided whereby the operation of the apparatus is rendered more sensitive and more responsive to the condition of the material. A typical such arrangement is shown in FIG. 12.

Referring now to FIGS. 1 and 4, there is shown an improved control arrangement for controlling the speed of the dryer reel 20 in accordance with the condition of the material approaching the reel. It will be understood that the control arrangements for other components of the dryer unit and related apparatus are similar, and the illustrated control apparatus may be considered represen-

tative of that employed elsewhere in the apparatus. Thus, as shown in FIG. 4, the arm 40 supporting the dancer roll 39 is pivotally mounted with respect to the housing wall 12, by means of a suitable shaft 77. The shaft 77 extends through the wall 12 of the housing and mounts a cam 78, the cam being rigidly secured to the shaft 77, for rotation therewith. The cam 78 has an active cam surface 78a which, in the operative positions of the cam, bears upon the outer end of a movable plunger 79, the arrangement being such that the position of the plunger changes as the cam 78 is rotated.

In the form of the invention illustrated in FIG. 4, the plunger 79 forms an active part of a control valve mechanism 80, shown in more detail in FIG. 5, the valve 80 being placed in series in a fluid line 81. The line 81 is connected with a source of fluid (advantageously air) under pressure and leads through a solenoid control valve 82 to a rotary air motor 83. The air motor 83 may be of a standard commercial type, and is advantageously of such design that the rotating parts thereof are of small size and low mass. A rotatable shaft 84, driven by the motor 83, extends axially from the motor and is connected to the worm 85 of a worm gear mechanism 86, mounted on the housing wall 12. The worm gear 87 of the mechanism 86 is keyed or otherwise secured to the shaft 88 (see FIG. 1) of the dryer reel 20, whereby, upon rotation of the shaft 84 and worm 85, the dryer reel is caused to rotate. Accordingly, as air under pressure is delivered through the valves 80, 82, to the motor 83, the motor is caused to operate at a speed determined by the pressure of the fluid supplied thereto.

To regulate the pressure supplied to the motor 83, and thereby control the speed of operation thereof, a regulator valve of the type shown in FIG. 5 may be employed. With reference to that figure of the drawing, the reference numeral 89 designates a valve housing having a chamber 90 therein connected in series with the fluid line 81. At the outlet end of the chamber 90 is a recess 91, one surface 92 of which forms a valve seat. A valve member 93, substantially in the form of a pin having an enlarged head, is received in the recess 91 and is adapted, in combination with the valve seat 92, to control the flow of fluid out of the chamber 90. A washer-like member 94 is secured to the housing, at the upper end of the chamber 90 to retain the enlarged head portion of the valve 93 within the recess 91, it being understood, however, that in normal operation the pressure differential resulting from the flow of fluid through the valve will tend to urge the valve member 93 toward the valve seat 92.

At a point along the stem portion of the valve member 93 is a bearing plate 95, which contacts the inner end of the plunger 79. The arrangement is such that the plunger 79, which is slidably mounted in the valve housing 89, is adapted to press against the valve member 93 to tilt the enlarged head portion thereof out of sealing engagement with the valve seat 92, appropriate means being provided, if necessary, to prevent disengagement of the plunger and bearing plate, as by preventing rotation of the bearing plate.

As the cam 78 is rotated with the shaft 77, the position of the plunger 79 with respect to the housing is varied, and the valve member 93 is tilted to a greater or lesser extent. This, in turn, varies the restriction at the valve outlet and controls the rate of flow of fluid through the valve.

As a general rule, the operative range of the cam 78 is such that the flow of fluid through the valve 80 is controlled only within certain design limits. Accordingly, it is advantageous to provide the solenoid valve 82, which may be controlled from a master control station, for opening and closing the fluid line 81. The arrangement is such that the fluid motor 83 may be quickly energized or de-energized by means independent of the cam 78.

In the operation of the drying unit, the arm 40, supporting the dancer roll 39, will tend to swing toward a

vertical position under the influence of gravity and against the restraining action of the material 37 which is passing around the roll. As the arm 40 moves toward a vertical position, the cam 78 is rotated to move the plunger 79 inwardly and increase the tilt of the valve member 93. This permits a less restricted flow of fluid through the valve 80 and causes the motor 83, and hence the dryer reel 20, to rotate at an increased speed. If the speed rotation of the reel 20 becomes too great, the web of material 37 will cause the arm 40 to move upwardly (clockwise as viewed in FIG. 1), so that the outlet opening in valve 80 is restricted somewhat and the speed of the reel is correspondingly decreased. As will be readily understood, the arm 40 will automatically seek a position in which the speed of rotation of the dryer reel 20 corresponds to the speed at which the material enters the dryer unit.

To regulate the speed of the lower dryer reel 21, a drive means 83a is provided, which is similar to the drive means for the first reel 20 and is controlled by the dancer assembly 41, 42. As shown in FIG. 11, the dancer assembly 41, 42 cooperates with a valve assembly 80a, similar to the valve 80, to control the speed of the reel 21 in a manner highly responsive to the tautness of the material travelling between the reels. The speed of the intake roller 35 and the subsequent processing apparatus, such as the folder of FIG. 8, or the intake roller of an adjacent dryer unit, where units are employed in multiple arrangement. Dancer arms 42, 45, illustrated in FIG. 1, are representative of advantageous, additional control means for controlling the speeds of the lower reel 21 and the folder, respectively.

As an alternative arrangement for controlling the speed of the dryer reels and other components of the dryer and related apparatus, a valve arrangement of the type shown in FIG. 6 may be substituted for the valve 80 of FIGS. 4 and 5. The valve 96 of FIG. 6 may, in general, be a valve of conventional construction, such as a "Cash-Acme Pressure Reducing and Regulating Valve," manufactured by A. W. Cash Valve Mfg. Corp., of Decatur, Illinois. However, whereas valves of the general type described ordinarily have a screw-operated regulating adjustment, the illustrated valve 96 incorporates a slideable plunger 97 which, by its vertical adjustment with respect to the casting of the valve, regulates the pressure at which fluid is discharged therefrom. The position of the slideable plunger is determined by means of a cam or eccentric 98 mounted on a shaft 99, corresponding to the shaft 77 of FIG. 4. The valve arrangement of FIG. 6 is advantageous in many instances in that it may be readily adapted for the purpose intended and provides accurate regulation of fluid flow.

Immediately following a drying operation, it is often convenient to fold the traveling web of material in flattened form. Known means for this purpose are described in United States Patent No. 2,761,678, issued September 4, 1956, to Eugene Cohn, et al. Such known means include an overhead feed means for feeding the material downwardly toward a surface adapted to support a folded pile of material, the feed means including a guide movable back and forth over the pile of material, to lay the material in a series of reverse folds. Thus, referring to FIGS. 8-10, the material 37, leaving the dryer, is drawn into the folder, about idler rolls 102 and 103 by feed roll 104 which is driven by an air motor 101, which may be similar to air motor 83, the supply of air to which is controlled by dancer roll 44, through an air valve 86b, such that the speed of the folder changes in accordance with the tautness of the material travelling from the second reel 21 to the folder. After passing over the feed roller 104, the material travels between a pair of guide rollers 105, 106 resting on an overhead support 107. The material 100 travels downwardly between the guide rollers 105, 106 onto a pile of flat, folded material 108, the arrangement being such that the guide rollers 105, 106 move

back and forth along the support 107 while simultaneously feeding the material 37 downwardly, so that the material folds back upon itself successively, in a series of flat folds.

While the folding mechanism shown in FIG. 8 may be otherwise as generally described in the aforementioned Patent No. 2,761,678, the apparatus of the present invention incorporates certain specific improvements relating to the movement of the guide rollers 105, 106 back and forth on the overhead support, while simultaneously positively feeding the material downwardly toward the pile 108. Thus, with reference to FIGS. 9 and 10, the supports 107 comprise horizontally disposed angle members 109 having on their upper surfaces elongated track members 110. The track members 110 are spaced apart a distance somewhat greater than the maximum width of material to be handled and have upper surface portions of inverted V-shaped cross section.

Guide rollers 105, 106 are supported by shafts 111, 112, respectively, which extend axially from the ends of the guide rollers, and adjacent the outer ends of the shafts 111, 112 are pulleys 113 having V grooves therein, the pulleys being arranged to be supported on the track members 110, for movement therealong. Advantageously, the track members 110 and pulleys 113 are so arranged that the pulleys 113 frictionally grip the track members, whereby upon movement of the pulleys along the track members the pulleys will be caused to rotate.

In accordance with the invention, the pulleys 113 are rotatably supported on the shafts 111, 112 and are rigidly connected to the driving elements 114a of overrunning clutches 114. The driven elements 114b of the overrunning clutches are keyed or otherwise secured to the guide roller shafts, whereby the guide rollers 105, 106 may be driven in one direction by rotation of the pulleys 113. In accordance with the invention, the overrunning clutches 114 are so arranged that the respective guide rollers 105, 106 are adapted to be driven in opposite directions.

Shown best in FIG. 10, the guide rollers 105, 106 are spaced a fixed distance apart by means of links 115 which engage projecting end portions of the shafts 111, 112, the spacing being such as to permit the web of material 37 to pass between the rollers while being gripped thereby.

Keyed or otherwise secured to the respective guide roller supporting shafts are gears 116 which are arranged in meshing relation, so that upon rotation of one of the guide rollers, the other guide roller is caused to rotate at the same speed in an opposite direction. The arrangement is such that rotation of the guide rollers causes the web of material to be fed downwardly between the rollers, with each of the rollers exerting a driving influence upon the material.

In order to move the guide rollers 105, 106 back and forth along the track members 110, a drive chain 117 is provided, the drive chain being entrained about sprockets 118, 119, the latter sprocket being driven synchronously with feed roller 104. One of the links of the drive chain 117 is pivotally connected to a driving arm 120 which, in turn, is pivotally connected to the shaft 111, by means of a bearing assembly 121. Accordingly, as the chain 117 moves unidirectionally throughout its cycle, the guide rollers 105, 106 are moved first in one direction and then the other along the track members 110.

As the guide rollers move in one direction along the track members 110, the pulleys 113 supporting both rollers will be caused to rotate in the same direction. In accordance with the invention, however, the arrangement of the overrunning clutches 114 is such that only one of the clutches will drive its associated guide rollers. For example, if the guide rollers move from right to left, as viewed in FIG. 8, the clutches associated with the guide roller 106 will be operative, and the guide roller 106 will be driven in a counterclockwise direction. At the same time, the guide roller 105 will be driven through the gears

116 in a clockwise direction, the clutch 114 associated with this guide roller merely overrunning during such rotation. When the rollers 105, 106 reach their innermost limit of right-to-left movement, and begin to move from left to right, the clutch associated with the roller 105 becomes operative, while the second clutch begins to overrun. This causes the roller 105 to be driven in a clockwise direction by its clutch, while the roller 106 is driven in a counterclockwise direction through the meshing gears 116. The arrangement is such, as will be readily understood, that the rotation of the guide rollers is the same regardless of the direction in which the rollers move along the track members 110.

In the normal operation of the folding apparatus of FIGS. 8-10, the guide rollers 105, 106 are moved continuously back and forth along the track members 110 at a rate corresponding to that at which the material is fed around the rollers 102, 103, 104. The feeding of material downwardly through the guide rollers 105, 106 takes place at a corresponding rate, so that the material is laid in neat, flat folds upon the pile 108.

The apparatus of the invention incorporates several advantageous features providing greater versatility in the use of the apparatus and improving the efficiency of the operation thereof. The new modular drying unit is so designed as to provide a complete unit having a drying capacity suitable for businesses having minimum drying requirements. Thus, material processors having such minimum requirements may reduce equipment expense to a practical minimum and at the same time realize a substantial savings in factory floor space. Businesses requiring additional drying capacity may utilize the modular units in multiple arrangement, in a manner best suited to their particular demands. Thus, in all cases, the drying apparatus may be utilized with maximum effectiveness.

One of the advantageous features of the new modular unit resides in the ease with which the unit may be alternatively adapted for individual or multiple use. In this respect, a dryer unit adapted for individual use, or for use as the last dryer for a multiple series, advantageously includes means to cool the material as it leaves the dryer. In accordance with the invention the means to cool the material may be readily converted into means to heat the material, whereby to add additional drying capacity to the dryer units, where appropriate and desirable. The new dryer unit also incorporates several advantageous structural features, including an improved structure for the hot air ducts, improved arrangements for directing the flow of drying air uniformly across the material, and improved arrangements for drawing fresh air into the dryer to replace moisture-laden air discharged therefrom.

Another important advantageous feature of the invention resides in the provision of improved control arrangements for regulating the speed of various material conveying components of the dryer and of apparatus related thereto. To this end, the invention incorporates a simple fluid driven motor, actuated by a fluid system including a solenoid-operated cut-off valve and a variable pressure regulating valve, the latter being operated automatically in accordance with the condition of the material adjacent the respective conveying components. The new control arrangement is highly sensitive and responds quickly to changes in the condition of the material, so that the traveling web of material is maintained under desired tensions at all times.

The invention also provides improvements in folding devices, advantageously used following drying operations, whereby a pair of material-feeding guide rollers may be caused to move back and forth over a support while simultaneously feeding the material thereto, so that the material is laid in a series of flat folds. In this respect, the invention provides a simplified and improved mechanism for driving the guide rollers to feed the material in the manner desired.

It should be understood, however, that the specific ap-

paratus illustrated and described herein is intended to be representative only, as certain changes may be made therein without departing from the clear teachings of the invention. Accordingly, reference should be made to the following appended claims in determining the full scope of the invention.

We claim:

1. In a dryer unit for a traveling web of material, the combination of a housing, means in said housing forming a drying chamber, a dryer reel in said chamber, means to feed a web of material onto said reel, means including a heater to direct streams of heated air toward said web as it passes around said reel, means in said housing forming an elongated cooling passage communicating with said drying chamber and positioned to receive heated material leaving said reel, sealing means forming an opening of limited size at the entrance end of said cooling passage and substantially isolating said cooling passage from said drying chamber, cooling air duct means communicating with said cooling passage, and cooling air blower means for delivering cooling air to said cooling air duct means, whereby streams of cooling air may be discharged into said cooling passage and onto the heated web therein.

2. The dryer unit of claim 1, in which said sealing means includes removable sealing elements, said cooling passage and drying chamber being in substantial communication when said sealing elements are removed, whereby heated drying air may be directed into said cooling passage, and means are provided for selectively rendering said cooling air blower means inoperative to discharge cooling air into said cooling passage.

3. The dryer unit of claim 2, characterized by said sealing means including a pair of rolls defining a nip through which said web passes in moving from said drying chamber to said cooling passage.

4. The dryer unit of claim 2, characterized by said means to direct heated air comprising hot air duct means disposed about a substantial portion of the periphery of said reel, and a hot air blower for circulating heated air under pressure to said hot air duct means, said hot air duct means and said cooling air duct means being formed in part by removable sealing elements, said sealing elements forming, at least in part, said sealing means and being removable to connect said hot air and cooling air duct means whereby hot air may be directed into said cooling passage, and means are provided for selectively rendering said cooling air blower means inoperative to discharge cooling air into said cooling passage.

5. In a dryer for a traveling web of material, the combination of a unitary housing, a dryer reel mounted for rotation in said housing, said dryer reel being of cylindrical form and having a generally open cylindrical wall structure accommodating passage of air radially into the interior of said reel, said dryer reel having opposite end openings each having an area substantially as large as the external end area of the reel, hot air duct means mounted within said housing and embracing a substantial circumferential area of said dryer reel, said duct means extending from one end to the other of said dryer reel and having openings for discharging air generally radially toward said reel, said duct means having spaced end walls extending transversely to the axis of said reel, said housing including opposite side walls spaced outward from

the end walls of said hot air duct means a substantial distance and forming substantially enlarged end chambers immediately adjacent and in communication with the end openings of said dryer reel, each of said end chambers having a transverse area at least as large as the combined areas of an end opening of the reel and the area of an end wall of said duct means, blower means having intake means communicating with said enlarged end chambers, and heater means mounted within said enlarged end chambers and disposed between the end walls of said duct means and the side walls of said housing, said heater means being positioned between the end openings of said reel and the blower intake means.

6. The apparatus of claim 5, in which said housing side walls are spaced from said duct end walls a distance not substantially less than fifty-percent of the diameter of the reel.

7. In combination, a pair of modular dryer units for fabrics and the like, a first of said units comprising a housing, means including a heater, a blower and a hot air duct for directing heated air upon a web of material passing through a first portion of said housing, auxiliary air duct means for directing hot air upon said web of material passing through a second portion of said housing, said auxiliary air duct means being connected to said hot air duct, and a second of said units being arranged with its entry end in series relation with the exit end of said first unit as regards movement of the web, said second unit comprising a second housing, means including a second heater, a second blower and a second hot air duct for directing heated air upon said web of material passing through a first portion of said last mentioned housing, means including a second blower and a second auxiliary air duct means for directing cooling air upon said web of material passing through a second portion of the last mentioned housing, and sealing means substantially isolating said first and second portions of said last mentioned housing.

8. The modular dryer unit of claim 7 in which said sealing means further include a pair of sealing rollers through which said web of material passes, said rollers substantially isolating the second portion of said housing from hot air within the first portion of said housing while permitting the travel of said web of material into and through the second portion of said housing.

UNITED STATES PATENT OFFICE
CERTIFICATE OF CORRECTION

Patent No. 3,065,551

November 27, 1962

Samuel Cohn et al.

It is hereby certified that error appears in the above numbered patent requiring correction and that the said Letters Patent should read as corrected below.

Column 5, line 27, for "col" read -- cool --; line 59, for "On" read -- One --; column 6, line 58, for "preceeding" read -- preceding --; lines 67 and 68, strike out "A typical such arrangement is shown in FIG. 12." and insert the same after "48.", in line 5, same column 6; column 8, line 25, for "The" read -- Similar means may be utilized to control the --; column 9, line 62, for "undirectionally" read -- unidirectionally --; column 11, lines 24, 32, and 36, for the claim reference numeral "2", each occurrence, read -- 1 --.

Signed and sealed this 22nd day of October 1963.
